[57] CLAIM

The ornamental design for combined headset and handset video game, as shown and described.

DESCRIPTION

FIG. 1 is a top, front, left perspective view of my combined headset and handset video game;
FIG. 2 is a top plan view of the headset thereof;
FIG. 3 is a bottom plan view of the headset thereof;
FIG. 4 is a front elevational view of the headset thereof;
FIG. 5 is a rear elevational view of the headset thereof;
FIG. 6 is a right elevational view of the headset thereof;
FIG. 7 is a left elevational view of the headset thereof;
FIG. 8 is a top plan view of the handset thereof;
FIG. 9 is a bottom plan view of the handset thereof;
FIG. 10 is a rear elevational view of the handset thereof;
FIG. 11 is a front elevational view of the handset thereof; and
FIG. 12 is a left side elevational view of the handset thereof; and
FIG. 13 is a right side elevations view of the handset thereof. The headset and handset are shown separately in FIGS. 2-7 and FIGS. 8-13, respectively, for clarity of illustration.
